UNITED STATES PATENT OFFICE.

EDWARD C. DENNERT, OF DETROIT, MICHIGAN, ASSIGNOR TO FRANK KUHN, OF DETROIT, MICHIGAN.

SAFETY ATTACHMENT FOR BOTTLES CONTAINING POISON OR THE LIKE.

Application filed May 12, 1924. Serial No. 712,677.

The invention relates to safety attachments for bottles containing poison or the like and has for one of its objects the provision of an improved safety attachment which indicates 5 that the bottle to which it is attached contains poison or the like. Another object is the provision of a safety attachment which is attachable to the bottle in such a way that a child is not liable to remove the same. 10 Further objects of the invention reside in the novel features of construction as more fully hereinafter set forth.

In the drawings:

Figure 1 is a side elevation of a bottle having applied thereto a safety attachment embodying my invention;

Figure 2 is a plan view thereof;

Figure 3 is a plan view of the safety attachment upon the completion of the first 20 operation in the manufacture of the same.

1 is the bottle having the neck 2 with the annular bead 3 at its upper end. 4 is the cork insertable within the neck. 5 is the safety attachment detachably engageable 25 with the bottle and comprising the body 6 which extends over the cork and the downturned resilient arms 7 having at their lower ends the inturned portions 9 engageable with the underside of the bead 3 and terminating 30 in the return-bent end portions 10 which extend adjacent to and preferably contact with the neck 2. 11 is a member extending upwardly from the body 6 and preferably shaped to serve as a warning that the bottle 35 contains poison or the like.

The safety attachment 5 is preferably stamped from a sheet metal blank and as shown in Figure 3, the body 6, arms 7, and member 11 are in the same plane, with the 40 arms and member extending from the edge of the body, upon the completion of the first operation in the manufacture. The member is subsequently bent to extend upwardly from the body 6 and the arms are subsequently bent to extend downwardly from the body and have the inwardly extending portions as 45 well as the return bent portions.

The arms of the safety attachment may be readily sprung over the bead 3 and into engagement with the neck 2 below the bead. 50 The return-bent ends form thumb portions permitting of springing the arms outwardly to remove the attachment. The arrangement is such that a child would ordinarily fail to detach the safety attachment, because 55 this safety attachment can be removed only by springing the arms outwardly and then moving the safety attachment bodily away from the bottle.

What I claim as my invention is:

1. The combination with a bottle having a neck with a bead at its upper end and a cork insertable within said neck, of a stamping comprising a body extending over said cork, downturned resilient arms projecting from 65 the periphery of the said body and having a snap engagement with said neck below said bead, and an upturned member projecting from the periphery of the said body and bearing insignia to denote danger. 70

2. The combination with a bottle having a neck with a bead at its upper end and a cork insertable within said neck, of a stamping comprising a body extending over said cork, downturned resilient arms projecting from 75 the said body and engageable with said neck having means at their lower ends for hindering the removal of said stamping when encountering said bead, and an upturned member projecting from the periphery of the said body representing a skull and crossbones. 80

3. A safety attachment for bottles comprising a stamping having a circular body portion and a plurality of projections extending radially therefrom, one of the said 85 projections being bent upwardly to form a warning member and the remaining projections being bent downwardly to form arms resiliently engageable with the bottle.

In testimony whereof I affix my signature.

EDWARD C. DENNERT.
